UNITED STATES PATENT OFFICE.

ALLEN T. DEXTER, OF CLEVELAND, OHIO, ASSIGNOR TO THE NATIONAL MALLEABLE CASTINGS COMPANY, OF CLEVELAND, OHIO.

MANUFACTURE OF CAST-STEEL CHAIN.

1,365,771.

Specification of Letters Patent. Patented Jan. 18, 1921.

Application filed June 7, 1919. Serial No. 302,568.

To all whom it may concern:

Be it known that I, ALLEN T. DEXTER, a citizen of the United States, residing at Cleveland, Cuyahoga county, Ohio, have invented new and useful Improvements in Apparatus for the Manufacture of Cast-Steel Chain, of which the following is a specification, reference being had to the accompanying drawings, in which—

10 Figure 1 is a plan of a mold box embodying my invention; Fig. 2 is an elevation on lines II—II of Fig. 1, partly in section; Fig. 3 is an elevation thereof with the pattern pieces in operative position; 15 Fig. 4 is an elevation similar to Fig. 3 but with the pattern pieces withdrawn from the box; Fig. 5 is a sectional detail of a pair of complementary pattern pieces; Figs. 6, 7 and 8 are details of the mechanism for 20 locking the complementary pattern pieces together; and Fig. 9 is a perspective of a mold section produced by my improved mold box.

25 My invention relates to the making of cast steel chain links in the form of a continuous chain and consists in apparatus for making simultaneously a plurality of sand mold sections for casting of chain links therein. My invention also consists in the 30 construction and arrangement of parts which I shall hereinafter describe and claim.

35 Referring to the drawings, the core box consists of four compartments or single core boxes arranged side by side. Each compartment comprises sides 2, ends 3 and bottom 4. Secured to the bottom 4 of each compartment is a pattern piece 5 in the form of a half link on a longitudinal line of division and having portions of its sides cut away at 40 6. These pattern pieces 5 form the impressions A in which are intended to be placed precast links, and as it is not necessary that these precast links be entirely inclosed within the mold each mold section is made

45 narrower than the width of a link to save sand and space. Mounted within each end of each of the compartments is a curved end draw piece 7, which is removable through the end of the compartment. Also in each 50 compartment are two curved bottom draw pieces 8, each of which is complementary to an end draw piece 7, and forms with the piece 7 a quarter link impression. Each bottom draw piece 8 extends through the

bottom of the box and is pivoted at the center of its curvature on a trunnion 9. In order to save time in withdrawing the pieces 7, there being a set of pieces 7 at each end of the compartments, the pieces in each set are connected to a common draw- 55 head 10, of which there are two, one for each set. Each drawhead 10 is equipped with handles 11 by which it is operated. Secured to the end of the drawhead 10 and lying close to the sides of the box are the 60 curved slotted guides 12, the slot being curved about the same center as the curve of the draw piece 7. Each trunnion 9, of which there are two, has pivoted to it all 65 of the bottom draw pieces 8 at that end of the box, so that when a trunnion 9 is rotated all of the pieces 8 connected to it are simultaneously withdrawn through the bottom of the box. Secured to each end of each trunnion 9 and lying outside of the box are the 70 levers 13. These levers 13 are connected by means of links 14 to the slotted guide 12, so that when the drawheads 10 are pulled away from the box the end draw pieces 7 are 75 withdrawn through the ends of the box and the bottom draw pieces 8 are rotated about the trunnions 9 and withdrawn through the bottom of the box. Attached to the box and seated in the curved slot of each guide 12 is 80 a pair of studs 15 which cause it to operate 85 in an arc parallel to the arc of the end draw pieces 7, and one of which acts as a limiting stop for the guide.

The guides 12 and drawheads 10 accordingly have a movement similar to that which 90 would be obtained if these parts were similarly pivoted at the center of curvature of the end draw pieces 7. As is indicated in Fig. 4, the operation of moving the drawheads 10 away from the box simultaneously 95 withdraws all of the draw pieces 7 and 8 from the box, and thereby frees these pieces from within the molded sand.

In one end of each compartment, as is shown in Fig. 2, is a removable draft piece 100 16 tapered on its outer side and matched up with the corresponding taper in the adjacent end of the compartment. Secured to this piece 16 is a pattern piece 17 which forms a part impression for a gate in the 105 sand through which the metal is subsequently poured into the mold. At the opposite end of each compartment is a pattern

piece 18, which on its inner face corresponds to the pattern piece 17. The draft piece 16 and the pattern pieces 17 and 18 are apertured to permit the removal of the draw pieces 7 and 8 therethrough.

The operation of molding is as follows:

With the box as shown in Figs. 1 and 2, sand is rammed into the various compartments and in and around the various pattern pieces 5, 7 and 8, and is jolted down. A core plate (not shown) is clamped over the top of the box and the box inverted. The draw pieces 7 and 8 are then removed through the bottom and ends of the box and the box lifted off the molded sand, carrying with it the pattern pieces 5. When the core box is lifted from the mold sections the parts 10 16, 17 and 18 remain with the mold sections, and after the box has been removed they are 15 withdrawn laterally from the mold sections. 20

To prevent each pair of complementary pieces 7 and 8 from being shaken apart during jolting, in the end of each piece 8 is secured a dowel 19, and through each piece 7 25 passes a shaft 20, which extends out through the drawhead 10, as is best shown in Fig. 5. On the inner end of the shaft 20 is a locking pin 21, which is passed through a slot 22 in the dowel 19. Then, when the shaft 20 is 30 rotated, the pin 21 bears against the shoulder formed by the inner face of the dowel 19. At the outer end of the shaft 20 is a handle 23 and a locking member 24. Secured on the outer side of the drawhead 10 is a cam 35 surface 25, as is shown in Fig. 7. As the shaft 20 is rotated so as to lock into the piece 8 the member 24 rides up the cam 25 and thereby draws the piece 8 securely against the piece 7 and thus holds the parts 40 7 and 8 securely together and rigidly against the drawhead 10. The inner end of the draw piece 7 is recessed, so that the tapered end of the dowel 19 fits snugly within it to hold the draw pieces 7 and 8 accurately in 45 alinement. It is to be understood that I prefer to employ the construction just described in each compartment, but for simplification of the drawings I have shown it in connection with only one compartment in Figs. 50 1 and 2.

In Fig. 9 I have shown a completed quarter mold section which contains on one face thereof an incomplete half impression A for a preformed link, and within the body 55 of the section two separate quarter link impressions B which extend within the impression A and intersect the plane thereof. Each mold section has at each end a part impression b of a stud of a link, each of which connects with an impression B, and also (except when used as a bottom mold section) a part impression c for a pouring gate, each

of which communicates respectively with an impression B.

It will be seen that by use of the foregoing apparatus a plurality of mold sections can be made simultaneously, thereby increasing the speed at which the sections can be made, greatly increasing the output, and cheapening the manufacture of mold sections.

The terms and expressions which I have employed are intended to be used as terms of description and not of limitation, since I recognize that modifications of the features 75 and constructions which I have described may be made within the scope of the invention claimed.

What I claim is:

1. A box for forming cast chain link 80 molds, comprising a plurality of compartments, pattern pieces in each compartment to form part impressions for links within the body of the mold sections, and means for removing the pattern pieces simultaneously 85 through guide ways in the ends and bottom of the box.

2. A box for forming cast chain link 90 molds, pattern pieces to form part impressions for links within the body of the mold sections, means for removing the pattern pieces through guide ways in the sides and bottom of the box, and means for holding the pattern pieces for each part impression rigidly together during the molding operation.

3. A box for forming cast chain link 95 molds, comprising a plurality of compartments, pairs of complementary pattern pieces in each compartment, each pair to 100 form part impressions for links within the body of the mold sections, guideways in the ends and bottom of the box and means for removing the pattern pieces simultaneously through said guideways.

4. A box for forming cast chain link 110 molds, comprising a plurality of compartments, complementary pattern pieces in each compartment, each pair forming within the body of a mold section a quarter link impression, lever mechanism for oppositely and simultaneously withdrawing the complementary pairs from within the box to permit the removal of the mold sections from the box.

5. A box for forming cast chain link 115 molds, a pattern piece secured to the bottom of the box, and pattern pieces mounted in a plane at right angles to the plane of the first named pattern piece, and removable through the side and bottom of said box, and means for simultaneously removing said last named pattern pieces.

ALLEN T. DEXTER.
